(57) **CLAIM**

The ornamental design for a gland follower with integral loading cylinders for a rotary or reciprocating mechanical device, as shown and described.

DESCRIPTION

FIG. 1 is a top front perspective view of a gland follower with integral loading cylinders for a rotary or reciprocating device showing my new design;

FIG. 2 is a top plan view thereof;

FIG. 3 is a bottom plan view thereof;

FIG. 4 is a front elevational view thereof with the back elevational view being the same;

FIG. 5 is a right side elevational view thereof with the left side elevational view being the same; and

FIG. 6 is a top plan view showing the two elements of my gland follower spaced apart; and,

FIG. 7 is a top front perspective view of the two elements of FIG. 6.
